US0D1104854S

(12) **United States Design Patent** (10) **Patent No.:** **US D1,104,854 S**
(45) **Date of Patent:** **** Dec. 9, 2025**

(54) **BUCKLE**

(71) Applicant: **ZEDEL**, Crolles (FR)

(72) Inventor: **Paul Petzl**, Barraux (FR)

(73) Assignee: **ZEDEL**, Crolles (FR)

(**) Term: **15 Years**

(21) Appl. No.: **29/903,135**

(22) Filed: **Sep. 20, 2023**

(30) **Foreign Application Priority Data**

Mar. 21, 2023 (EM) 015015215-0002

(51) **LOC (15) Cl.** **02-07**

(52) **U.S. Cl.**

USPC **D11/218**

(57) **CLAIM**

The ornamental design for a buckle as shown and described.

DESCRIPTION

FIG. 1 is a front, left-side, top perspective view of a buckle, showing the new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof; and,

FIG. 7 is a bottom plan view thereof.

The broken lines depict parts of the buckle that form no part of the claimed design.

1 Claim, 7 Drawing Sheets
